Primary Examiner — Brian N Vinson*(74) Attorney, Agent, or Firm* — J. Douglas Wells(57) CLAIM

The ornamental design for a horticulture grow light, as shown and described.

DESCRIPTION

FIG. 1 is a perspective view of a horticulture grow light, as viewed from below, showing my new design;

FIG. 2 is a perspective view of the light shown in FIG. 1, as viewed from above;

FIG. 3 is a left side view of the light shown in FIG. 1;
FIG. 4 is a right side view of the light shown in FIG. 1;
FIG. 5 is a front elevation view of the light shown in FIG. 1;FIG. 6 is a rear elevation view of the light shown in FIG. 1;
FIG. 7 is a bottom plan view of the light shown in FIG. 1;
and,FIG. 8 is a top plan view of the light shown in FIG. 1.
The broken-line disclosure shown in the views is understood to represent portions of the article in which the claimed design is embodied, but which form no part of the claimed design.1 Claim, 7 Drawing Sheets| (56)	References Cited
